UNITED STATES PATENT OFFICE.

GEORGE B. KURTZON, OF CHICAGO, ILLINOIS, ASSIGNOR TO GARDEN CITY PLATING & MANUFACTURING COMPANY, OF CHICAGO, ILLINOIS, A FIRM COMPOSED OF GEORGE B. AND MORRIS KURTZON.

TRACK FOR SLIDING DOORS.

1,254,706.

Specification of Letters Patent. Patented Jan. 29, 1918.

Application filed June 25, 1917. Serial No. 176,765.

To all whom it may concern:

Be it known that I, GEORGE B. KURTZON, a citizen of the United States, and a resident of the city of Chicago, county of Cook, and State of Illinois, have invented certain new and useful Improvements in Tracks for Sliding Doors, of which the following is a specification.

My invention relates to tracks or runners for supporting and guiding sliding doors, windows and similar closures for display counters, cabinets and the like.

One of the objects of my invention is to economize material in the construction of a track or runner of this character. Another object is the provision of a device of this kind that may be readily stamped out of commercial forms of angle metal, that are purchasable in the open market, or from a flat blank of metal. Other objects are the provision of a track or runner constructed in the manner above mentioned that is dependable and effective in its operation, economical to manufacture, and comparatively simple in its structure.

Other objects and advantages will be obvious to others after an understanding of my invention is had, and I prefer to accomplish the divers objects by the means and in the manner hereinafter fully described, reference being had to the accompanying drawings that form a part hereof:—

In the drawings,—

Figure 1 is a perspective view of a short length of track made in accordance with my invention and drawn to an enlarged scale.

Fig. 2 is a top plan thereof, and

Fig. 3 is a vertical transverse section thereof on line 3—3 of Fig. 2.

Fig. 4 is a transverse section of a modified form of my invention.

Fig. 5 is a fragmentary top plan of the modification shown in Fig. 4.

Referring to the drawings, it will be observed my invention comprises a length of metal of substantially right-angle or L-shaped cross-section, the upper edge of the vertical flange 5 whereof affords the tread upon which the sliding door, window or other structure is supported and guided, while the horizontal flange 6 provides the base or support for said tread portion and is provided with a desirable number of holes 7,

through which screws are passed for securing the track in position in its proper place. 55

Tracks of the type thus described have been used for the same purpose for which I have designed my improved track, but it has been found that the weight of the structure supported thereby has a tendency to and 60 actually does strain the horizontal or base flange for the reason that the weight is entirely along one edge of flange 6 and therefore is not evenly distributed, hence the opposite edge is pried up and loosened from 65 the supporting structure. In order to overcome this inherent objection, I prefer to punch or stamp out suitable portions 8 of the metal of the vertical flange 5 and bend them laterally thereto so that they will lie in substantially the same plane with the base or horizontal flange 6, as shown in Figs. 1, 2 and 3. These stamped out portions 8 provide lateral lugs or feet that extend outwardly from the flange 5 upon the side 70 thereof opposite the base flange 6, and suitable holes 9 are formed in said lugs through which screws may be passed to secure the track rigidly in position.

In lieu of stamping or punching out the 80 lugs 8 from the metal forming the tread flange 5, said lugs may be readily stamped or punched out of the base flange 6, as shown in Fig. 4, and bent under until they are disposed at substantially right angles to the 85 vertical track flange and in alinement with the base flange, in which event the screw holes 7 will necessarily have to be staggered with relation to the lugs, which will not detract from the effectiveness of the device. 90

It will be observed that the lateral lugs project from the side of the track opposite the base flange and thus act as a brace and prevent the tipping of the track by relieving the screws in holes 7 of approximately one-half their strain. I am aware that inverted T-shaped metal bars have been employed for tracks and runners, but as this material is usually sold by weight, I effect a material saving, both in material and cost, by stamping out the bracing lugs from one of the flanges of right angle or L-section metal strips. 95

What I claim as new is:—

1. A track or runner for sliding doors 105 comprising a strip of metal of substantially

L-shaped cross-section, and lateral bracing lugs stamped out of one of the flanges of said strip and extended in alinement with the horizontal flange thereof.

5. 2. A track or runner for sliding doors comprising a strip of metal of substantially L-shaped cross-section, and lateral bracing lugs stamped out of one of the flanges of said strip and extended opposite to and in 10 alinement with one of said flanges whereby said lugs and the flange opposite thereto constitute a base for carrying and securing the other of said flanges vertically to provide the requisite track.

15. 3. A track or runner for sliding doors comprising a strip of metal bent mediate its longitudinal edges to provide an upright flange and a lateral flange at substantially right angles thereto whereby a track base of

substantially L-shaped cross-section is provided, and lateral bracing lugs stamped out of the upright flange and extended in alinement with the horizontal flange thereof. 20

4. A track or runner for sliding doors comprising a strip of metal of substantially 25 L-shaped cross-section, and lateral bracing lugs stamped out of the vertical flange of said strip and extended into alinement with the horizontal flange thereof whereby a structure of substantially T-shaped cross- 30 section is provided at the locations of said lugs.

Signed at Chicago, county of Cook and State of Illinois, this 12th day of June, 1917.

GEORGE B. KURTZON.
